ATTORNEY:

UNITED STATES PATENT OFFICE

115,788

DESIGN FOR A CABINET FOR A RADIO BROADCAST RECEIVER OR SIMILAR AR- TICLE

Arthur C. Haggstrom, Rockford, Ill.

Application December 13, 1938, Serial No. 81,763

Term of patent 7 years

To all whom it may concern:

Be it known that I, Arthur C. Haggstrom, a citizen of the United States, having residence in Rockford, in the county of Winnebago, State of Illinois, have invented a new, original, and ornamental Design for a Cabinet for a Radio Broadcast Receiver or Similar Article, of which the following is a specification, reference being had to the accompanying drawing, forming a part thereof.

In the drawing:

Fig. 1 is a perspective view of a cabinet for a radio broadcast receiver or similar article embodying my new design.

Fig. 2 is a top plan view of the same.

It may be understood that the rear wall is substantially flat, and that the two sides of the cabinet are similar, as indicated in Fig. 2.

The characteristic features of my design are shown in solid black lines in the drawing. The cabinet of this design is also adapted to be used as a television receiver cabinet.

I claim:

The ornamental design for a cabinet for a radio broadcast receiver or similar article, substantially as shown and described.

ARTHUR C. HAGGSTROM.
